UNITED STATES PATENT OFFICE.

HENRY N. GAGEL, OF DAYTON, OHIO.

DESIGN FOR A COLUMN FOR CREAM-SEPARATORS.

SPECIFICATION forming part of Design No. 30,673, dated May 2, 1899.

Application filed April 8, 1899. Serial No. 712,329. Term of patent 7 years.

To all whom it may concern:

Be it known that I, HENRY N. GAGEL, a citizen of the United States, residing at Dayton, in the county of Montgomery and State of Ohio, have invented a certain new and useful Design for a Column for Cream-Separators; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

Figure 1 is an elevation showing my new design. Fig. 2 is a plan view of the upper or lower end.

As shown in the drawings, the leading or material feature of my design consists of the

two flaring or funnel-shaped ends A A' and 26 the intervening round or tubular portion B. The latter provides a narrow or contracted passage from one end to the other. The ends are substantially the same in dimensions. One of said ends—to wit, A'—serves as a supporting-base for the column and is provided with a series of holes A''.

Having described my invention, I claim and desire to secure by Letters Patent—

The design for a column for a cream-sepa- 30 rator, as herein shown and described.

In testimony that I claim the foregoing as my own I hereto affix my signature in presence of two witnesses.

HENRY N. GAGEL.

Witnesses:

W. B. NEVIN,
R. J. McCARTY.
